LÜBECK, GERMANY.

DIVER'S HELMET.

1,252,780.

Specification of Letters Patent.

Patented Jan. 8, 1918.

Application filed October 8, 1914. Serial No. 865,740.

To all whom it may concern:

Be it known that we, FERDINAND LUDWIG CLAREN and HERMANN STELZNER, subjects of the German Emperor, and both residing at Lübeck, Germany, have invented certain new and useful Improvements in Divers' Helmets, of which the following is a specification.

In divers' dresses or apparatus it is frequently desirable to manufacture the helmet as well as other parts of the apparatus of a light material. Frequently the helmet is made integral with the upper part of the dress and preferably of pliable water proof fabric, rubber or the like material or on the other hand the helmet is made of removable parts, which are of particularly light construction in order to reduce the weight of these parts. Light helmets constructed in this manner have the drawback that their buoyancy is so large that it places a considerable strain upon the muscles of the liver to hold the helmet, when working, out of the vertical position.

This drawback is avoided according to the present invention by providing the helmet with removable weights or loads.

Removable weights on divers' dresses have been previously used but not in connection with helmets for the object explained above.

Preferably a single removable weight is applied to the top of the helmet for the purpose hereinafter described.

Fig. 1 is a front elevation of a diver's dress, the helmet of which is constructed according to the present invention.

Fig. 2 is a side view of the upper part of the dress, and

Fig. 3 is a similar view of a modification. Fig. 4 shows a diver in working position furnished with another modification of the invention.

In the construction shown in Figs. 1 and 2 the removable weight for the helmet *a* consists of a U-shaped hoop *b*, which is so constructed, that the end portions *b'* thereof rest on the shoulders of the diver and both the chest weight *c* and the back part of the diving apparatus *d* can be attached to the shoulder portions by means of cords *c'*, *d'*, respectively.

In the modification shown in Fig. 3, the weight takes the form of a crest *r*, which owing to its formation is very pliable and can be easily removed.

In the modification shown in Fig. 4, the weight *b'* is disk shaped. This modification has certain advantages. It might seem natural to distribute the weight on the helmet, so that the center of gravity lies in the center of buoyancy. However it seems to be more advantageous to arrange the additional weight on the very top of the helmet as is shown in Fig. 4, in which the diver is seen working in a bent or stooping position. In this position the center of buoyancy may be considered to be at 1, while the chest weight is attached to the helmet at 2. If however the weights are so distributed that the center of gravity is also at 1, such a weight would have to be comparatively large. When however the weight is concentrated at the top of the helmet as shown in Fig. 4, in which the center of gravity will be at a considerable distance from the center of buoyancy a reduction of the weight will be possible to a great extent.

When the helmet, instead of being made of a rigid material is made of a pliable fabric or the like, it is of advantage to make use of a metal cap on the top of which the additional weight *b'* is attached, and which protects the pliable helmet against injury.

If so desired the cap itself may be so constructed as to form the additional weight *b'* itself. Such a cap can be easily made removable and if desired can be perforated.

We claim:

The combination of a diver's helmet and a removable U-shaped hoop adapted to rest on the shoulders of the diver and extend over the top of the helmet, a chest weight and the back part of the diving apparatus attached to the shoulder portions of the hoop.

FERDINAND LUDWIG CLAREN.
HERMANN STELZNER.
